HENRY F. METZLER, OF NEW YORK, ASSIGNOR TO HIMSELF AND WILLIAM F. YOUNGS, OF BROOKLYN, NEW YORK.

Letters Patent No. 77,513, dated May 5, 1868.

IMPROVEMENT IN SPRING-HORSES.

The Schedule referred to in these Letters Patent and making part of the same.

TO ALL WHOM IT MAY CONCERN:

Be it known that I, HENRY F. METZLER, of the city of New York, in the county of New York, and State of New York, have invented a new and useful Improvement in Spring-Horses; and I do hereby declare that the following is a full, clear, and exact description thereof, reference being had to the accompanying drawings, and to the letters of reference marked thereon, in which—

Figure 1 is a longitudinal section of the base-frame which supports the horse, the vibrating-standard on which the horse is mounted, and the spiral spring which aids in keeping up the vibratory motion.

Figure 2 is a front view of the vibrating standard which carries the horse, and

Figures 3 and 4 are views of the two ends of the spiral spring D, showing the means of securing and attaching said ends respectively.

This invention is an improvement upon the "spring-horse" heretofore invented by me, and described in Letters Patent issued to myself and Thomas G. Copperthwaite, (assignees of myself,) bearing date the 21st day of February, 1865, and numbered 46,529.

The spring-horse described in said patent is caused to vibrate by the child's touching its feet to the base-frame or stationary base-piece, in front and rear of the vibrating-standards alternately, and at each touch of its feet making a sufficient jump or spring to carry the horse, (with the child mounted thereon,) and with the aid of the spiral springs described in said patent, over the perpendicular point, and land the child's feet on said base-frame at the opposite end. By means of my invention all necessity of the child's touching its feet to the base-frame, or to any other stationary object, is obviated, and the horse is made to leap or vibrate by the child pressing its feet at the proper times upon a foot-support, which is attached to the vibrating-standard, and vibrates therewith.

A is the stationary base-frame; B, the vibrating-standard, on which the horse (not shown in the drawings) is mounted; C is a rock-shaft, on which the standard B is mounted; and D is a spiral spring, which brings the vibrating-standard back to a perpendicular position whenever it is inclined in either direction. One end of this spring is made fast to the front end of the base-frame A, and the other end is hooked at e to a bracket, E, attached to the base of the vibrating-standard B, and the rock-shaft C on which said standard is mounted. It will be seen that whether said standard B be inclined forward or rearward, the spring will be drawn out or expanded, and by its contraction will tend to bring said standard back to its perpendicular position. F is a cross-bar, which constitutes a foot-rest or stirrup for the child. It is attached to the vibrating-standard B by means of a screw and nut, f, and is adjustable to suit a child of any size, by moving it up or down, the screw-bolt f moving in a slot, b, in the standard B. The horse is mounted on the standard B at H. When the child bears its whole weight on the horse, an inclination of the body forward or rearward will cause the horse and the standard B to incline in the same direction, but if the child throws its weight upon the foot-rest F, the leverage is so diminished that the spring D will bring the horse back to a vertical position, when the child releases the pressure with its feet, and by a slight inclination of the body, causes the horse to pass the vertical point and vibrate to the desired distance. Thus, by alternately pressing with its feet on the foot-rest F, and releasing the pressure, and by a slight and natural movement of the body, the child is enabled to keep up a vibrating, leaping motion of the horse, quite similar to the natural movements of a living horse. I regard this as a valuable improvement upon my former mode, which requires the child to make a jump or spring from the floor or base-frame, for each leap of the horse.

The spring-horse described in the former patent referred to, is mounted on two vibrating-standards, and this I regard as necessary to produce the best motion, by preventing the horse from coming to too great an angle to the horizon, at the extremities of the vibrations. But as my improvement is equally applicable to a horse mounted on one or two standards, I have in the drawing represented but one. When two vibrating-standards are used, as described in said former patent, the foot-rest will be attached to the front standard, which will bring it in the proper position for the child's feet. Two spiral springs may be used, one in front and one in rear of the vibrating-standards, as represented in said former patent.

Instead of a ratchet-wheel and pawl to regulate the tension of the spiral spring, as described in my former patent, I now use a simple thumb-screw, *i*, passing through the cross-bar at the end of the base-frame, and a nut, *j*, to which the end of the spiral coil is attached. By turning the screw *i*, the tension of the spiral spring may be increased or diminished.

I also use an improved means of attaching the ends of the spiral spring, consisting of a cross-bar, *j j'*, with a hole in each end large enough to insert the wire. The extremity of the coiled wire is first passed through one end of said cross-bar, which is then slipped around until the same extreme end of the wire will pass through the other end of the bar. Said cross-bar may then be attached to any object by a hook, link, pivot, screw, or other fastening. I find it a better means of securing the end of a spiral spring than any I have hitherto known. The cross-bar *j* in this case forms the nut for the screw *i*.

Having thus fully described my invention, what I claim as an improvement upon my aforesaid former invention, and desire to secure by Letters Patent, is—

1. The adjustable foot-rest, vibrating with the horse, substantially as described.
2. The cross-bars *j* and *j'*, to secure the ends of the spiral spring, and as a means of attaching the same to the screw *i*, and bracket *E*, substantially as described.

HENRY F. METZLER.
